UNITED STATES PATENT OFFICE.

EMANUEL E. GUINGRICH AND CHRISTIAN L. MILLER, OF CARLOCK, ILLINOIS.

MACHINE ELEMENT.

1,110,050.

Specification of Letters Patent.

Patented Sept. 8, 1914.

Application filed August 16, 1913. Serial No. 785,100.

To all whom it may concern:

Be it known that we, EMANUEL E. GUINGRICH and CHRISTIAN L. MILLER, citizens of the United States, residing at Carlock, in the county of McLean and State of Illinois, have invented certain new and useful Improvements in Machine Elements, of which the following is a specification, reference being had to the accompanying drawings.

10 This invention relates to machine elements, and it more particularly relates to an improved form of attachable and removable sprocket wheels.

One of the objects of the invention is to provide a device of this character which is especially applicable as an element of seed sowers, manure and fertilizer distributors, and such other machines and devices that are designed to be carried by an ordinary wagon 20 or cart and operated thereby.

Another object of the invention is to provide a sprocket or gear wheel of this character which may be quickly, easily and securely fastened onto a wagon or cart wheel, 25 in concentric relation therewith, and removed therefrom, without removing the wagon wheel, and without disuniting any of the elements of the gear wheel. And another object is to provide a gear member of 30 this character which is simple of construction, strong, durable, comparatively inexpensive and thoroughly practical and efficient.

In the accompanying drawings, which 35 supplement this specification, Figure 1 is an elevation view of the device applied to a wagon wheel, the latter being illustrated in broken lines; Fig. 2 is an end elevation view, partly in section, of the device applied 40 to the spokes of a wagon wheel; Fig. 3 is an edge elevation view; Fig. 4 is an enlarged elevation view of the device from the opposite side of Fig. 2; Fig. 5 is a view of the device in open position and in the position 45 for placing it on a wagon wheel; Fig. 6 is a fragmental edge view, illustrating one of the joints of the rim sections in detail and in open position; Fig. 7 is a fragmental edge view of the hinge joint, as viewed from the 50 inside when in open position; Fig. 8 is a perspective detail view of the hinge connection and joint of the rim sections; and Fig. 9 is a sectional view through the rim section 6 contiguous to one of the hook bolts 55 or clamping members.

In these drawings, in which similar ref-

erence characters correspond with similar parts throughout the several views, the numeral 5 designates a wagon wheel, onto four spokes of which is secured the main element 6 or body portion 6 of the sprocket rim by means of clamps 7. These clamps may be of any preferred and proper construction; but in the present illustration, the clamps 7 each consists of a pair of hook-bolts 7', a 65 yoke 7^a, nuts 7^b, and an apertured lug 6', the latter being formed integrally with the body member 6. These four apertured lugs are spaced apart substantially 90 degrees between their centers, and between two adjacent lugs 6' is provided a space sufficiently wide for the axle of any ordinary wagon to be passed laterally therethrough, and this space is filled by a segmental rim section 8, the ends of which rest upon the shoulders 9 70 which are formed by the projecting ends of the contiguous lugs 6'. Adjacent to one end of the body or C-shaped rim section 6, recesses 10 are provided at opposite sides, to provide seats for the hinge elements or 75 spaced circumferential extensions 8' of the segmental element 8, a pivot 11 extending through said extensions and through an aperture which communicates with the recesses 10, in the body 6. The opposite end 80 of the body 6 is provided with a slot 12, while the contiguous end of the element 8 is provided with a tongue 13 which fits snugly in the slot 12. It will be seen, therefore, that the elements 6 and 8 combine to 85 form a complete annular wheel rim, and on this rim may be provided any desired number, pitch, and design of teeth 14.

An apertured lug 15 is secured to the section 6, adjacent to one end portion, while 90 a similar lug 15 is provided on the section 8, for engagement with a flexible and yieldable element 16, which may consist of a chain and a retractile spring, as illustrated, or may consist of any other proper and suitable means for drawing and holding the segmental section normally seated firmly in its seat on the shoulders 9. However, it is obvious that the action of the chain or other member with which this gear wheel engages 100 presses said segment more firmly into its seat.

In applying the device, the segmental section 8 is swung manually on its hinge or pivot 11, against the action of the spring 110 or yieldable element 16, so that the space between the ends of the body 6 may be

passed over the axle of the wagon wheel, in a direction at right angles to said axle, whereupon, the element 8 is released and allowed to be seated on the shoulders 9. It will be seen that the yieldable element 16 lies in a chordal plane of the device, so as not to interfere with the axle of the wagon. The nuts 7^b and yokes 7^a are now removed, and the lugs 6' are seated against the contiguous spokes of the wheel 5, whereupon, the yokes and nuts are replaced, and the latter are tightened after the rim of the wheel has been properly centered; that is, located concentrically with the axle of the wagon. It is proposed to employ, in connection with a sprocket wheel of this character, a chain composed of removable links, so that it may be lengthened or shortened, as desired; and so, when it is desired to change the speed of the machine or mechanism which is to be driven by a sprocket of this character, a larger or smaller sprocket wheel may be quickly and easily substituted for the one which is being employed. In other words, these sprocket wheels are interchangeable with each other, and they may also be fitted onto wagon wheels of different sizes and having different size spokes.

30 While we have described this device as having four apertured lugs, it would obviously be within the scope of my invention to increase or decrease the number of lugs 15, to increase or decrease the number of apertures therein, or to extend these lugs circumferentially, axially or radially to any extent desired.

40 It will be seen that we have provided a machine element of this character which is fully capable of attaining the foregoing objects in a thoroughly practical and efficient manner and that the invention is not confined to a sprocket wheel, but is also applicable to different forms of gear wheels.

45 While the accompanying drawings illustrate what we believe to be the preferred embodiment of our invention, it is to be understood that the invention is not limited thereto, but that various changes may be

made in the construction, arrangement and proportions of the parts without departing from the scope of the invention, as defined in the appended claims.

We claim:

1. A detachable gear wheel for wheeled vehicles, comprising a rim section having a portion thereof cut away to receive an axle, a segment pivoted to one end of the cut-away portion and extending thereacross to provide a substantial continuation of the gear teeth, said segment being formed at its free end with a shoulder, and the adjacent end of the rim section being formed with a shoulder adapted to coact with the first-named shoulder, a spring secured to the under surface of the segment and to the inner surface of the section, and means carried by the section for securing it to adjacent wheel spokes, whereby said section may be fixedly clamped in a position concentric with the axle.

2. A detachable gear for wheeled vehicles comprising a gear section having a cut away portion, a gear segment pivoted to said section to swing across said cut away portion, means resiliently urging said segment into closing position, off-set blocks formed at spaced intervals on the gear section and adapted to engage against wheel spokes and each provided with bores disposed transversely of the adjacent spoke on either side thereof, a plate adapted to engage against the other face of the spoke and to extend on either side thereof, and J-bows having their shanks passed through the ends of said plates and having their bills disposed in the bores of the off-set blocks whereby the gear may be fixedly clamped in a position concentric with the axle and spaced from the wheel.

In testimony whereof we hereunto affix our signatures in the presence of two witnesses.

EMANUEL E. GUINGRICH.
CHRISTIAN L. MILLER.
